SHOCK ABSORBER

Filed Aug. 10, 1929

Inventor:
Frederick T. Elliott,
by Walter E. Lombard. Atty.

UNITED STATES PATENT OFFICE

FREDERICK T. ELLIOTT, OF SOMERVILLE, MASSACHUSETTS

SHOCK ABSORBER

Application filed August 10, 1929. Serial No. 384,963.

This invention relates to shock absorbers for automobiles, the object of the invention being the production of an inexpensive but efficient device of this character which will be double acting and retard the movement of the car springs gradually during the compression and recoil of said springs.

This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings:

Figure 1 represents a vertical section of a shock absorber embodying the principles of the present invention, the cutting plane being on line 1, 1, on Fig. 2.

Figure 2 represents a section of the same on line 2, 2, on Fig. 1.

Figure 3 represents an inverted plan of a portion of the oscillating shaft.

Figure 4 represents a plan of a portion of said oscillating shaft.

Figure 5 represents a section of same on line 5, 5, on Fig. 4.

Figure 6 represents a section of same on line 6, 6, on Fig. 3.

Figure 7 represents a section on line 7, 7, on Fig. 1.

Figure 8 represents a section of the inner ring of the stuffing box surrounding the oscillating shaft, and

Figure 9 represents an elevation of a portion of the partition within the oil chamber.

Similar characters indicate like parts throughout the several figures of the drawings.

In the drawings, 10 is a casing having a cylindrical chamber 11 therein which is closed by the cover 12 threaded to said casing.

The rear wall of the casing 10 has a cylin-

drical depression 13 formed therein within which is disposed one end of an oscillating shaft 14, the opposite end of which extends through a stuffing box 15 on the cover 12 and has keyed to its outer end an arm 16.

The outer end of the arm 16 is pivotally connected in any well known manner to the frame of the automobile while the casing 10 is secured to the body of the automobile by bolts extending through the ears 17.

The shaft 14 has a radial blade 18, the outer end of which abuts the cylindrical wall of chamber 11 while the opposite edges thereof abut the inner wall of casing 10 and the inner face of cover 12.

To the inner wall of casing 10 is secured a partition 19 by means of bolts 20 extending through the ears 21 formed on said partition, the upper end of said partition contacting with the periphery of the oscillating shaft 14.

The lower end of said partition 19 has set in a groove therein a packing strip 22.

The partition 19 and blade 18 divide the chamber 11 into two compartments *a* and *b* and the entire chamber 11 is adapted to be filled with oil or other liquid.

Under normal conditions the blade 18 is vertical as shown in Fig. 1 of the drawings, but when the car springs are compressed and the body of the car moves downwardly relatively to the car frame, said blade 18 will be moved in the direction of the arrow *c* on Fig. 1.

The shoulder 23 on the partition 19 will limit the downward movement of said blade 18 but as a matter of fact, the blade 18 will never contact with said shoulder 23 when the chamber 11 is filled with oil.

Cut into the lower part of the periphery of the oscillating shaft is a crescent shaped groove 24 of greater depth in the center than at either end as shown in Fig. 1.

Centrally disposed in the upper end of the partition 19 is a vertical passage 25, the upper end of which communicates with one end of a depression 26 in said partition opposite the groove 24.

The opposite end of said depression 26 com-

municates with the compartment *a* of the chamber 11.

The lower end of the passage 25 communicates with a lateral passage 27 in which is disposed a ball 28 normally on a valve seat 29 and preventing flow of oil from the "b" compartment to the "a" compartment of chamber 11.

The ball valve 28 is retained in the passage 10 27 by the projections 30.

When the blade 18 moves in the direction of arrow *c* oil will be forced into the groove 24 and depression 23 and the greater portion of this oil will enter the passages 25 and 27 15 forcing the ball 28 from its seat 29 against the projections 30, thus permitting said oil to pass around the ball 28 into the compartment *b*.

At the same time a small portion of the 20 oil will pass from compartment "a" to compartment "b" through the shallow end 31 of the groove 24.

As the blade 18 commences to move from its normal position as shown in Fig. 1, the 25 oil displaced will enter the deepest part of the crescent shaped groove 24 but as said blade 18 continues to move in the direction of arrow *c*, the shallow end 32 of said groove 24 will be moved opposite the depression 26 30 and retard the passage of oil from compartment *a* to compartment *b* and prevent too great a compression of the car springs.

As the blade 18 starts on its return movement oil in compartment *b* entering passage 35 27 will force the ball valve 28 to its seat 29 and close the passage 25 so that no oil from compartment *b* can flow to compartment *a* through this passage 25.

40 All oil, therefore, passing from compartment *b* to compartment *a* must pass through the groove 24 which is wide open at the initial return movement of the blade 18 but gradually closes, thus permitting a decreased quantity of oil to pass through said groove 24.

45 Owing to the crescent shape of the groove 24 and the gradual closing thereof during the oscillation of the shaft 14, all shock is effectively prevented both when the car springs 50 are compressing or when recoiling.

It is self-evident, therefore, that a double acting shock absorber is provided which will take up the shock when the body of the vehicle is moving downwardly and will gradually retard its movement in the opposite direction.

The shaft 14 is provided with a by-pass between the two compartments of chamber 11 which may be wholly opened, or entirely or 60 partially closed to regulate the action of the blade 18 by supplying an additional means for the flow of oil from one compartment to the other.

This by-pass consists of two radial passages 65 33 on opposite sides of the blade 18 and com-

municating at their inner ends with the chamber 34.

These passages are preferably offset as shown in Fig. 4.

Centrally disposed in the shaft 14 is an 70 adjustable member 35 threaded to said shaft, as at 36 and having a flattened portion 37 at its inner end.

As shown in the drawings both passages 33 are open and oil may pass freely between the 75 two compartments in either direction.

By adjusting and rotating the member 35 either passage 33 may be closed or partially closed and this operation will control the movement of the blade 18 decreasing or increasing the speed thereof as desired.

At the inner end of the stuffing box 15 is a metal ring 38 surrounding and in contact with the periphery of the shaft 14.

This ring 38 has in its periphery an annular recess 39 from which a plurality of openings 40 extend to the inner cylindrical wall thereof.

A conduit 41 in the cover 12 communicates at one end with the recess 40, the opposite end 90 communicating with a passage 42 in the partition leading to one of the compartments of the chamber 11.

Any oil forced outwardly around the shaft 14 will pass through the openings 40 into the 95 recess 39 from which it will flow through the passage 42 into the compartment *a*.

The oil is prevented from flowing in the opposite direction by the ball valve 43 retained in the enlarged exit end of the conduit 100 41 by the projections 45.

This makes a very simple form of shock absorber, easily constructed, but very effective in operation.

It is believed that the operation and many 105 advantages of the invention will be understood readily without further description.

Having thus described my invention, I claim

1. The combination of a casing having an inner chamber with a cylindrical wall; a centrally disposed oscillating shaft in said chamber having a single crescent shaped groove in the periphery thereof and provided with an imperforate radial blade substantially opposite said groove and abutting the walls of said chamber; and a single radial partition in said chamber extending from the wall of said chamber to said shaft and coacting with said blade to divide said chamber into two compartments, said partition having a valved passage therethrough always communicating at one end with said groove.

2. The combination of a casing having an inner chamber with a cylindrical wall; a centrally disposed oscillating shaft in said chamber having a single crescent shaped groove in the periphery thereof and provided with an imperforate radial blade sub-

stantially opposite said groove and abutting the walls of said chamber; a single radial partition in said chamber extending from the wall of said chamber to said shaft and 5 coacting with said blade to divide said chamber into two compartments, said partition having a passage therethrough always communicating at one end with said groove; and a valve in said passage permitting the 10 flow of oil in one direction only.

3. The combination of a casing having an inner chamber with a cylindrical wall; a centrally disposed oscillating shaft in said chamber having a single crescent shaped 15 groove in the periphery thereof and provided with an imperforate radial blade substantially opposite said groove and abutting the walls of said chamber; a single radial partition in said chamber extending from the wall of said chamber to said shaft and 20 coacting with said blade to divide said chamber into two compartments, said partition having a passage therethrough always communicating at one end with said groove; 25 a by-pass through said shaft communicating with said compartments adjacent the opposite faces of said blade; and means within said shaft for regulating the passage of oil through said by-pass.

4. The combination of a casing having an inner chamber with a cylindrical wall; a centrally disposed oscillating shaft in said chamber having a single crescent shaped groove in the periphery thereof and provided with 35 an imperforate radial blade substantially opposite said groove and abutting the walls of said chamber, said shaft having two radial holes therein communicating with both compartments at points adjacent the opposite 40 faces of the blade; a single radial partition in said chamber extending from the wall of said chamber to said shaft and coacting with said blade to divide said chamber into two compartments, said partition having a valved 45 passage therethrough always communicating at one end with said groove; and a member adjustable endwise in said shaft and adapted to regulate the passage of oil through said radial holes.

5. The combination of a casing having an inner chamber with a cylindrical wall; a centrally disposed oscillating shaft in said chamber having a single crescent shaped groove in the periphery thereof and provided with 55 an imperforate radial blade substantially opposite said groove and abutting the walls of said chamber; a single radial partition in said chamber extending from the wall of said chamber to said shaft and coacting with 60 said blade to divide said chamber into two compartments, said partition having a valved passage therethrough always communicating at one end with said groove; a ring surrounding said shaft having an annular peripheral recess 65 and a plurality of openings extending therefrom to the inner wall of said ring; and a conduit from said recess to one of said compartments.

6. The combination of a casing having an inner chamber with a cylindrical wall; a centrally disposed oscillating shaft in said chamber having a crescent shaped groove in the periphery thereof and provided with a radial blade abutting the walls of said chamber; a partition in said chamber extending to 75 said shaft and coacting with said blade to divide said chamber into two compartments, said partition having a valved passage therethrough communicating at one end with said groove; a ring surrounding said shaft having an annular peripheral recess 80 and a plurality of openings extending therefrom to the inner wall of said ring; a conduit from said recess to one of said compartments; and a valve in said conduit permitting the flow of oil in one direction only. 85

7. The combination of a casing having an inner chamber with a cylindrical wall; a centrally disposed oscillating shaft in said chamber having a single crescent shaped 90 groove in the periphery thereof and provided with an imperforate radial blade substantially opposite said groove and abutting the walls of said chamber; and a single radial partition in said chamber extending from the wall of said chamber to said shaft and coacting with said blade to divide said chamber into two compartments, said partition having at its inner end a depression always communicating with said groove and 95 one of said compartments and provided with a valved passage leading from the inner end of said depression to the other compartment.

8. The combination of a casing having an inner chamber with a cylindrical wall; a centrally disposed oscillating shaft in said chamber having a single crescent shaped groove in the periphery thereof and provided with an imperforate radial blade substantially opposite said groove and abutting the walls of said chamber; a single radial partition in said chamber extending from the wall of said chamber to said shaft and coacting with said blade to divide said chamber into two compartments, said partition having at its inner end a depression always communicating with said groove and one compartment and provided with a passage leading from the inner end of said depression to the other compartment; and a valve in said passage permitting the flow of oil in one direction only. 105 110 115

9. The combination of a casing having an inner chamber with a cylindrical wall, a centrally disposed oscillating shaft in said chamber having a single crescent shaped groove in the periphery thereof and provided with an imperforate radial blade substantially opposite said groove and abutting the walls of said chamber; a single radial 120 125 130

partition in said chamber extending from the wall of said chamber to said shaft and coacting with said blade to divide said chamber into two compartments, said partition having at its inner end a depression always communicating with said groove and one compartment and provide with a valved passage leading from the inner end of said depression to the other compartment; a by-pass through said shaft communicating with said compartments adjacent the opposite faces of said blade; and means for regulating the passage of oil through said by-pass.

10. The combination of a casing having an inner chamber with a cylindrical wall; a centrally disposed oscillating shaft in said chamber having a crescent shaped groove in the periphery thereof and provided with a radial blade abutting the walls of said chamber; a partition in said chamber extending to said shaft and coacting with said blade to divide said chamber into two compartments, said partition having at its inner end a depression extending from one side of the partition and normally opposite the deepest part of said groove and provided with a passage from the inner end of said depression to the opposite side of said partition; and a valve in said passage permitting the flow of oil in one direction only.

Signed by me at 746 Old South Building, Boston, Massachusetts, this 9th day of August, 1929.
